UNITED STATES PATENT OFFICE.

NICHOLAS F. EGLER, OF CHICAGO, ILLINOIS, ASSIGNOR TO DUFF PATENTS COMPANY, OF PITTSBURGH, PENNSYLVANIA, A CORPORATION OF PENNSYLVANIA.

REVERSING VALVE FOR FURNACES.

Application filed March 20, 1925. Serial No. 16,995.

To all whom it may concern:

Be it known that I, NICHOLAS F. EGLER, a citizen of the United States, and a resident of Chicago, in the county of Cook and 5 State of Illinois, have invented a new and useful Improvement in Reversing Valves for Furnaces; and I do hereby declare the following to be a full, clear, and exact description thereof.

10 My invention relates to reversing valve structures for use in connection with open hearth furnaces and the like.

One object of my invention is to provide a structure wherein the reversal of 15 flow of gases from the furnace or furnaces to a stack may be controlled within a single hood or chamber and by a single valve.

Another object of my invention is to simplify and improve generally the structure 20 and operation of devices of this general type.

One form which my invention may take 25 is shown in the accompanying drawing wherein Fig. 1 is a view, partially in side elevation and partially in section, showing somewhat diagrammatically, apparatus embodying my invention; Fig. 2 is a plan view of the apparatus; Fig. 3 is a side elevational view of the structure of Fig. 2; 30 Fig. 4 is a view similar to that of Fig. 3 but showing certain of the parts in section, and Fig. 5 is an end elevational view.

The apparatus comprises a furnace 6, only 35 a portion of which is shown, having gas inlet passages 7 and 8 controlled by valves 9 and 10, respectively, and leading to the furnace or furnaces. The valves 9 and 10 may be of any suitable type. Furnace flues 11 and 12 are provided for alternately conducting products of combustion to the stack or chimney flues 13. The flues 11—12—13 40 extend through a casting 14 that is provided with water receptacles 15 for cooling a reversing valve 16. The valve 16 and 45 the flues are covered by a hood 17 that may be of somewhat the usual form. The reversing valve 16 is movable from the position shown in full lines in Figs. 1 and 4 to that shown in dotted lines therein, by 50 mechanism that will be hereinafter described.

Sheaves 18 are provided at each side of the hood 17 for guiding ropes 19 each of which is secured at one end to an eye member 19^a and passes over sheaves 20 and 21

and is provided with a counterweight 22 at its outer end whereby it may counter-balance the valve 16 and permit smoother movement thereof. The eye members 19^a are secured to the outer leg portions of 60 U-shaped members 23. The inner leg portions 23^b of these members are secured to the valve 16. The outer leg portions 23^a of the members 23 are provided with rollers 25 that travel along arcuate tracks 26 65 when the valve 16 is moved between the furnace flues 11 and 12. The weight of the valve is carried mainly by the rollers 25 and the counterweights 22.

The valve is operated by means of a lever 70 27 secured to a rock shaft 27^a and connected to pull chains 28. A pair of crank arms 29 are connected to the rock shaft 27^a and to a pair of links 30 which are in turn pivotally connected at 31 to the outer legs 23^a 75 of the U-members 23.

Links 32 are provided, each of which has one end pivotally connected to one of the members 23, at 31, and its other end is supported by a shaft or pin 33. The members 23 and the valve 16, which is carried thereby, are thus supported, at opposite sides of their center of gravity, by the links 32, counterweights 22, and the rollers 25. The tracks 26 are of such curvature that they 80 co-operate with the links 32 to maintain the valve 16 in substantially horizontal position when moving from one position to another.

By reference to Figs. 1 and 4 it will be 85 seen that when the upper end of the lever 27 is actuated by the pull chains 28, the valve 16 will be caused to travel from the position indicated in full lines to that indicated in dotted lines, or vice-versa. The position of 90 the valve determines which of the furnace flues 11 and 12 shall have communication, through the hood 17, with the stack or chimney flue 13.

When the flue 12 is covered by the valve 95 16 the gas valve 10 is opened and the gas valve 9 closed, so that gas will flow through the inlet 8, the furnace, (not shown) furnace flue 11, hood 17 and the gas flue 13, in the direction indicated by the arrows. When it 100 is desired to reverse the flow of gases through the furnace, the gas valve 10 is closed; the valve 16 shifted to the furnace flue 12, and the gas valve 9 is opened so that the flow through the furnace to the 105

2
stack flue 13 will be in substantially the direction reverse to that shown by the arrows.

From the foregoing it will be seen that I provide a single valve and a single valve chamber for controlling the direction of gas flow through a furnace, it being necessary only to operate the gas valves 9 and 10 to change the point at which the gas is admitted to the furnace, whenever the furnace 10 valve 16 is reversed, and that the valve 16 is always out of the path of the flow of hot gases.

I claim as my invention:

1. Furnace valve structure comprising a 15 valve chamber, a pair of furnace flues communicating therewith, a stack flue communicating therewith, and a valve movable to close either of the furnace flues, the stack flue being located between the furnace flues.
2. Furnace valve structure comprising a 20 valve chamber, a pair of furnace flues communicating therewith, a valve for closing either of the furnace flues, a gas inlet communicating with one of the furnace flues,

and a gas inlet communicating with the 25 other furnace flue.

3. Furnace valve structure comprising a valve chamber, a hood member therefor forming the upper portion thereof, a pair of furnace flues communicating with said chamber at a point below said hood, a stack flue disposed between said furnace flues, and a valve movable to close either of the furnace flues.

4. Furnace valve structure comprising a 35 valve chamber, a hood member therefor forming the upper portion thereof, a pair of furnace flues communicating with said chamber, a stack flue communicating with said chamber at a point below said hood, a 40 valve for closing either of said furnace flues, a gas inlet communicating with one of the furnace flues, and a gas inlet communicating with the other furnace flue.

In testimony whereof I, the said NICHOLAS 45 F. EGLER, have hereunto set my hand.

NICHOLAS F. EGLER.
